PORTABLE ENCLOSURE

Leon J. Davidson, 29 Carlton Circle, Andover, Mass.
Filed Dec. 19, 1962, Ser. No. 245,828

6 Claims. (Cl. 280—36)

This invention relates to a portable enclosure of the type generally referred to as a playpen. Its ordinary purpose is to provide a place in which small children may be placed to play or rest in safety. It may, of course, be used for other purposes, but in the explanation

of its construction and operation it will be considered in the light of its principal use.

Many types of playpens are known to the art. In the construction herein disclosed, there will be seen a number of features made possible by novel constructional elements which result in greater utility, simplification of operation, and low manufacturing cost.

The playpen of my construction is of variable width. When in minimum width condition, it is capable of passing through the ordinary household door. It is also subject to being reduced in vertical dimension to an extent permitting it to be placed quite easily in an automobile while still retaining sufficient wall height to act as a crib.

The invention further contemplates vertical wall support members of novel construction which may be removed from their connection with the wheel axles and from the floor in a manner permitting them to be swung first upwardly and then over and down on the floor to nest with each other while at the same time allowing the sides of the unit to collapse altogether, thus reducing the height of the device to only a little more than the vertical dimensions of the wheels. When in this condition, the unit occupies but little space and may be readily stowed in an automobile, closet, attic or even under a bed. While the supporting members that carry the floor and the top rail are made for convenience and strength in the general form of a W it will be understood that the vertical support members could be individual units without modifying the means for connecting them to the axles or to the floor.

Another important object of the invention is to provide a construction in which the floor may be shifted easily from small to large area. The small area floor is detachably connected to the vertical supports on one side in such manner that when the floor is enlarged by unfolding a portion thereof the long edge of the unfolded part may then be readily connected to the vertical supports in their widened position. When this is done, the larger floor is then supported fully as rigidly as it was in its condition of reduced area.

These and other objects of the invention will be more fully understood as the description proceeds with the aid of the accompanying drawings in which:

FIG. 1 is a perspective view of the playpen in its smallest usable dimension;

FIG. 2 is a view similar to FIG. 1 but with the vertical supports extended to give maximum depth;

FIG. 3 shows the playpen in its maximum dimension both vertically and horizontally with the floor opened for greatest area;

FIG. 4 is an enlarged view partly in section showing the telescoping nature of the top rails at the ends of the playpen;

FIG. 5 is a section on the line 5—5 FIG. 4;

2

FIG. 6 is a horizontal section on the line 6—6 of FIG. 3 showing the overlapped wall material in its maximum expanded condition;

FIG. 7 is a plan view on the line 7—7 of FIG. 2 to show 5 a portion of the floor construction in its small area condition with the mattress removed;

FIG. 8 is an enlarged fragmentary side elevation looking at the right of FIG. 7 showing the means for latching the floor to the vertical support and the means of attaching flexible wall material at the floor level;

FIG. 9 is an end elevation showing in solid lines the playpen in its reduced horizontal dimension and showing in dotted lines the manner in which the supports may be removed from the axles and the way in which the playpen may be extended laterally;

FIG. 10 is a vertical section on the line 10—10 of FIG. 2, showing the means of pivotally connecting the vertical supports to the upper rail;

FIG. 11 is an end view showing the vertical supports 20 in the process of being swung to inoperative horizontal position;

FIG. 12 is an end view similar to FIG. 11 showing the playpen in totally collapsed vertical condition with the supports nested as shown in FIG. 13; and

FIG. 13 is a plan view of FIG. 12 with the vertical supports in nested horizontal condition.

Referring first to FIGS. 1, 2, 3 and 9, the unit consists of a first pair of wheels 2, 2 mounted on fixed axle 4 and a second pair of wheels 6, 6 mounted on fixed axle 8. 30 The axles are secured together by horizontal straps 10 and 12 (see FIGS. 9 and 11) which curve upwardly at their near and far ends as at 14 and 16. To the upper ends of these four turned-up portions is secured the main floor 18 in any convenient manner, such as by small 35 bolts, for example. This portion of the structure just described consisting of the wheels, fixed axles, supports 14 and 16 and floor 18 is the basic rigid supporting foundation which is not subject to adjustment. The short dimension of the floor is approximately the length 40 of the axles 4 and 8, and in the preferred form will be in the order of 26 inches. Thus the playpen as shown in FIGS. 1 and 2 is capable of passing through any ordinary home doorway.

Along one of the long edges of floor 18 is a pair of 45 hinges 20 to which is affixed an overlying folded additional section of flooring 22 which when unfolded will assume the position shown in FIG. 3. When the floor is in folded reduced area condition, a suitable partially doubled floor pad or thin mattress 23 may be used to cover it. When the floor is unfolded, the floor pad 50 may be likewise unfolded to single thickness to be co-extensive with the floor in extended position as shown in FIG. 3.

The construction of the superstructure is as follows: A pair of W-shaped tubular elements 24 and 25 have 55 vertical portions 26 on the upper ends of which are telescoped extensions 28. At the bottom of each of the vertical portions 26 is a laterally extending plate 30 (decoratively cut to elephant profile) having a hole 31 therethrough whereby the plates may fit over the ends 60 of their respective axles 4 and 8 as at 32 and 34. Cotter pins 35 positioned in suitable holes in the axles are provided to hold the plates in place.

On the upper ends of the four telescoping extensions 28 is secured the upper frame comprising a U-shaped 65 portion 36 on one side with ends 37 and a generally simi-

lar U-shaped portion 38 with ends 39 on the other side. The dimensions of the ends 37 and 39, however, are such that they may telescope in an extensible manner. Latches 42 (see FIGS. 4 and 5) hold the telescoped ends 37 and 39 in contracted position. Other similar latches 43 are also provided to hold the portions 28 in extended position with respect to parts 26 as shown in FIG. 2. When latches 43 are released, the tubular parts 28 and 26 may be telescoped downwardly to the position of FIG. 1.

To further secure the vertical members 26, they are fastened to the floor at the four positions numbered 44 (see FIG. 2) by suitable latches 46, one of which is shown in detail in FIG. 8. Each of the four vertical parts 26 resides in a notch 47 in the floor. Each part 26 has a hole 48 extending transversely therethrough and into this hole may be moved latch 46 which is shiftable longitudinally through its guides 50 by the user from the released position shown in FIG. 8 to an engaged position to the right in which the righthand end of the latch extends through the hole 48. Two sets of guides 50 are fixed to the top of the folded floor 22 near hinges 20 as shown in FIG. 7, and two other sets of guides 50 are fixed directly to the top of floor 18 along the opposite side. By this construction, substantial rigidity is imparted to the W-shaped side members 24 and 25, these members being secured to the axles of both sets of wheels and to the floor by the latches 46 along the sides.

In shifting the vertical dimension of the playpen walls from that shown in FIG. 2 to the reduced height shown in FIG. 1, the latches 46 remain in locked position. The vertical extensions 28 upon release of latches 43 merely slide downwardly along tubular portions 26 to the extent of the available telescoping.

Between the upper rails 36 and 38 and the floor extends a suitable flexible enclosing material, preferably in the form of mesh or net 52 and 53. Net 52 may be attached to upper rail 36 through the use of attached plastic tape 54 which passes around the top of the rail and is riveted or cemented thereto as may be convenient (see FIG. 5). The net 52 that is attached to rail 36, including the telescoping ends 37, terminates in a vertical tape 56. The net 53 that is attached to rail 38, including the telescoping ends 39, terminates in a vertical tape 58. Thus between tapes 56 and 58 there are two layers of overlapping net when the playpen is in the condition of reduced lateral dimension as shown in FIGS. 1 and 2. On the other hand, when the playpen is extended to maximum dimension, as will be explained shortly, the tapes 56 and 58 and the attached nets are shifted to the position shown in FIG. 6 in which only the tapes overlap. In such condition, the tapes may be secured at spaced positions by snaps 60.

As can be seen in FIG. 5, the end portions of rail 38 indicated at 39 slide within the end portions 37 of rail 36. The parts 37 are longitudinally cut away as at 64 so that the horizontal tape 66 running along the upper part of net 53 may be secured to the under side of end portion 39 of rail 38. By this construction, it is obvious that the telescoping portions 37 and 39 may be moved longitudinally with respect to each other and the overlapping net portions 52 and 53 may move correspondingly. Where rail 38 is not telescoped, tape 66 passes thereover in the same manner that tape 54 surrounds rail 36. Thus the rails are both decorated and protected.

The lower edges of the end parts of net 52 and net 53 are similarly secured by tapes 61 and 62 to other telescoping tubular elements 68 and 70 best shown in FIG. 7. The element 70 is U-shaped and extends along the ends and side of the unit just below the floor 18. When the floor is unfolded so that the hinged part 22 is shifted to extended position, the U-shaped element 70 is correspondingly moved laterally so that the lower parts of the net 52 are extended, bringing the entire structure to the position shown in FIG. 3, in which the floor area is substantially a square of about 40 inches on a side. The

lower edge of net 53 below upper rail 38 may be permanently affixed to the floor 18 by upholsterer's tacks 63 (see FIG. 7) as there is no relative movement required at this position.

Before the playpen can be widened from the condition of FIGS. 1 and 2 to the enlarged size shown in FIG. 3, the following steps must be taken: First the cotter pins 35 must be withdrawn from the ends of axles 4 and 8. Then the bolts 46 must be withdrawn from their locked position in vertical members 26 of the W-shaped frame 24 on the side of the playpen at which the hinges 20 are located. As soon as this is accomplished, frame 24 may be swung away from the wheels as shown at position A in FIG. 9, the frame 24 pivoting on the hinges 72 that encircle the long side of frame 36. U-shaped frame 70, to which the lower part of net 52 is secured, is then drawn out to the position B shown in FIG. 9. When in this extended condition, the folded floor extension 22 may then be unfolded, pivoting about hinges 20 to drop down into flat position as shown in FIG. 3. In this position, floor extension 22 rests on extended U-shaped frame 70. (Mattress 23 is also shown in FIG. 3, being cut away in part to show the floor and frame 70.) Further support for floor extension 22 is needed, and this is achieved by extending leg 73 downwardly and then swinging W-shaped frame 24 back into position C shown in FIG. 9 in which parts 26 enter notches 74 (see FIG. 3) in the edge of floor extension 22 so that latches 76 secured to the edge of the floor at this position may be slid laterally to pass through openings 48 in parts 26. At this stage of assembly, folding floor portion 22 is connected to the two hinges 20 and the two elements 26 of W-shaped frame 24 and supported by leg 73 which rests on the underlying supporting surface. Additional support is given to frame 70 by the center portion of frame 24, which by means of a bolt and wing nut or other securing means is fastened to frame 70 as indicated at 78. In this final condition, the playpen, as seen in FIG. 3, is supported by the four wheels and leg 73, leg 73 being of sufficient strength to carry the load transmitted to elements 26 of frame 24.

If preferred, two separate foldable legs 73a and 73b, shown in dotted lines in FIG. 3, could be substituted for the single leg 73.

When the playpen is in the extended condition shown in FIG. 3, ends 37 and 39 of portions 36 and 38 are in minimum telescoped condition and vertical tapes 56 and 58 supporting the ends of nets 52 and 53 are in overlapping condition as shown in FIG. 6, in which position snaps 60 may be engaged to effectively seal the joint.

In the narrow condition of the playpen, as shown in FIGS. 1 and 2, leg 73 is swung up to horizontal position out of the way as it is not needed for support since frame 24 is carried directly by axles 4 and 8 through plates 30.

When the lateral dimension of the playpen is to be reduced from its maximum size, as shown in FIG. 3, to that of FIGS. 1 and 2, the above procedure is reversed. Wing nut 78 is removed to free W-shaped frame 24 from U-shaped member 70. Latches 76 are withdrawn from their engagement with elements 26 and frame 24 is swung outwardly, pivoting on hinges 72. With mattress 23 removed, hinged floor extension 22 is swung up and over to fall down on top of fixed floor 18. Latches 76 drop into openings 82 (see FIG. 3) so that floor extension 22 may parallel floor 18. Frame 70 is then pushed inwardly, telescoping with fixed tubular elements 68 until it reaches a position just inside notches 47. Upper rails 36 and 38 are then forced together with end portions 37 and 39 telescoping until the condition shown in FIGS. 1 and 2 is reached. At this point, latches 42 engage to hold the upper rail in reduced dimension condition. W-shaped frame 24 is then swung to position D in FIG. 9, at which point it enters notches 47 present in the edges of overlapping floors 18 and 22. In this position, plates 30 may be replaced on the ends of axles 4 and 8 and cotter

pins 35 reinserted. With vertical elements 26 located in notches 47, latches 46, which are secured to the now top side of folding floor portion 22, may be reinserted in openings 48. Finally the bolt and wing nut 78 may be reset through frame 70 and the middle part of frame 24 thereby to provide intermediate support for the floors 18 and 22.

From the description thus far, it can be seen that the playpen may readily have its vertical dimension changed through the telescoping of elements 25 and 28 and its width changed through the use of the telescoping upper rail portions 37 and 39 and the lower telescoping tubular elements 68 and 70.

Explanation will now be given of the manner in which the playpen may be reduced to minimum dimension to facilitate storage or transportation. Referring to FIGS. 9, 11, 12 and 13, the procedure is as follows: Cotter pins 35 are removed from both axles and all four latches 46 are withdrawn from engagement with the four vertical posts 26. Likewise the bolt and wing nut 78 is removed to free frame 24 from tubular element 70. Once this has been achieved, W-shaped frame 25 at the left as viewed in FIG. 9 and W-shaped frame 24 at the right, turning on their respective hinges 72 on rails 36 and 38, may be swung upwardly and over, each passing through an angle of approximately 270°. These two frames are shown on their way to final horizontal position in FIG. 11, whereas in FIG. 13 they are shown in final horizontal position directly on floors 18 and 22 from which mattress 23 has been removed. Since there is no longer any support for the side enclosing nets 52 and 53, the upper rails 36 and 38 drop down so that the whole upper structure then rests on floor 18 and the folded-over floor portion 22. This arrangement is shown in end view in FIG. 12 and in plan in FIG. 13 and represents the minimum dimension obtainable. In this position, it can be seen that the total height of the unit is but little more than the height of the wheels and the lateral dimension, in a preferred commercial construction, is in the order of 26 inches. Thus the unit can readily be stored in a small space, such as a closet, under a bed, or within an automobile.

If desired, a conventional foot brake mechanism 84 operated by a pedal 86 may be used, but this constitutes no part of the invention.

To reassemble the unit from the condition of FIGS. 12 and 13, reverse procedures are followed which will be obvious in view of the foregoing explanation.

It is my intention to cover all changes and modifications of the examples of the invention herein chosen for purposes of the disclosure which do not constitute departures from the spirit and scope of the invention.

I claim:

1. A playpen comprising supporting wheels and axles, a floor carried by said axles over said wheels, supports on opposite sides of said floor comprising two upwardly extending members detachably secured to the said axles, a top rail carried by the upper ends of said supports, flexible material secured to said floor and top rail and closing the space therebetween, said members rotatably secured to said rail and constituting the sole support therefor, whereby when said members are detached from said axles they may be swung to a position over said floor and said members, top rail and flexible material may drop to substantially the level of said floor.

2. A playpen comprising supporting wheels and axles, a floor carried by said axles over said wheels, supports on opposite sides of said floor comprising two upwardly extending members detachably secured to the said axles and to opposite sides of said floor, a top rail carried by the upper ends of said supports, flexible material secured to said floor and top rail and closing the space therebetween, said members rotatably secured to said rail and constituting the sole support therefor, whereby when said members are detached from said axles and floor they may be swung to a position over said floor and said members,

top rail and flexible material may drop to substantially the level of said floor.

3. A playpen comprising supporting wheels and axles, a laterally extendible floor carried by said axles over said wheels, supports on opposite sides of said floor comprising on each side two upwardly extending members detachably secured to the said axles and said floor when said floor is unextended, means for securing two of said upwardly extending members after detachment from said axles and unextended floor to the edge of said floor when extended, means for maintaining said extended floor substantially horizontal, an adjustable top rail carried by said members and means permitting adjustment to match the floor dimension, said members having telescoping portions above said floor whereby said top rail may be raised or lowered with respect to said floor, and flexible material secured to said top rail and floor and closing the space therebetween.

4. A playpen comprising supporting wheels and axles, a main floor carried by said axles over said wheels, supports on opposite sides of said floor comprising on each side two upwardly extending members of which those on at least one side are detachably secured to said axles and said floor, a continuous rectangular top rail carried by the said members, means for extending the area of said floor comprising an additional floor section overlying said main floor and connected thereto by hinges along the edge to which said members are detachably secured, said top rail being extensible along opposite ends thereof whereby when said members are detached from said axles and floor said top rail may be extended to a dimension substantially equal to the dimension of said main floor and additional floor section when the latter has been opened on said hinges, other means for connecting the said detachable members to the outer edge of said opened floor section, and means for supporting the said members when connected to the said opened floor section at the level required to maintain said floor section substantially in the plane of said main floor.

5. A playpen comprising supporting wheels and axles, a main floor carried by said axles over said wheels, supports on opposite sides of said floor comprising on each side two upwardly extending members which are detachably secured to said axles and said floor, a continuous rectangular top rail carried by the said members, means for extending the area of said floor comprising an additional floor section overlying said main floor and connected thereto by hinges along one edge, said top rail comprising two U-shaped sections with their respective ends telescoped whereby when said members are detached from said axles and floor on the side wherein said hinges are located said top rail may be extended to a dimension substantially equal to the dimension of said main floor and additional floor section when the latter has been opened on said hinges, other means for connecting the said detachable members to the outer edge of said opened floor section, and means for supporting the said members when connected to the said opened floor section at the level required to maintain said floor section substantially in the plane of said main floor.

6. A playpen comprising four wheels and axles on which said wheels are mounted, a main floor carried by said axles above said wheels, a floor extension section overlying said main floor and hinged to one side thereof, side supports comprising W-shaped tubular members, each member having each of its lower extremities detachably secured to an axle, latches on said main floor and floor section for detachably securing thereto the outer upwardly extending parts of said W-shaped members, vertically movable telescoping elements on the upper ends of said members, a rectangular tubular top rail carried by said telescoping elements, said rail having telescoping opposite side sections whereby said rail can be extended in the direction of opening movement of said floor extension section, said side support members rotatably mounted on

said top rail, whereby when said members have been detached from said axles and floor they may be rotated about said top rail to assume a horizontal overlapping position within said top rail on said floor, flexible material secured to said top rail and said floor to provide an enclosing wall when said side supports are in operative vertical position and carrying said top rail and adapted to collapse to ineffective position when said side supports have been detached from said axles and floor and have been rotated to said horizontal position on said floor. 10
